[57] CLAIM

The ornamental design for a combined credit card au-
thorization terminal and raised credit card imprinter, as
shown.

DESCRIPTION

FIG. 1 is a top front and left side perspective view of a
combined credit card authorization terminal and
raised credit card imprinter showing our new design;
FIG. 2 is a left side elevational view thereof on an en-
larged scale.

FIG. 3 is a front elevational view thereof on an enlarged
scale;

FIG. 4 is a top plan view thereof on an enlarged scale;
FIG. 5 is a right side elevational view thereof on an
enlarged scale;

FIG. 6 is a top, front, and left side perspective view of
a second embodiment of our new design;

FIG. 7 is a front elevational view thereof on an enlarged
scale;

FIG. 8 is a top plan view thereof on an enlarged scale;
FIG. 9 is a top, front, and left side perspective view of
a third embodiment of our new design;

FIG. 10 is a left side elevational view thereof on an
enlarged scale;

FIG. 11 is a front elevational view thereof on an enlarged
scale;

FIG. 12 is a top plan view thereof on an enlarged scale;
FIG. 13 is a right side elevational view thereof on an
enlarged scale.

The rear and bottom surfaces of the three embodiments
are unornamented. The left and right sides of the second
embodiment are identical to those of the first embodi-
ment as shown in FIGS. 2 and 5.
